BY Chester H. Braselton

ATTORNEY

UNITED STATES PATENT OFFICE.

CHARLES Y. KNIGHT, OF PASADENA, CALIFORNIA, ASSIGNOR TO KNIGHT AMERICAN PATENTS COMPANY, OF CHICAGO, ILLINOIS, A CORPORATION OF DELAWARE.

CYLINDER-HEAD CONSTRUCTION.

Application filed December 22, 1921. Serial No. 524,164.

My invention relates to improvements in cylinder heads for sleeve valve engines and has for its object to provide an improved take-up device between the head and packing or junk ring whereby all objectionable noises occasioned by the moving of the ring longitudinally upon the head may be eliminated.

Another object of the invention is to provide improved means for exerting pressure upon the junk ring longitudinally of the head to maintain a close fit between the two.

Another object of the invention is to provide, in combination with a sleeve valve engine, a junk ring between the head and the sleeve surrounding the head with improved means tending to constantly urge the ring upon the head to prevent it from shifting longitudinally thereon.

Another object of the invention is to provide, in combination with a sleeve valve engine, a junk ring upon the head and a retaining or tightening ring disposed upon one end of the junk ring, the tightening of the latter being afforded from time to time by the spreading or widening of the same at intervals, or the producing of enlargements thereon, which may be effected by the driving of a suitable tool into the metal to separate the particles thereof.

To these and other ends the invention embodies the novel construction and combination of parts shown and described herein and is intended to cover any such modifications as may fall within the scope of the appended claims.

One embodiment of the invention is illustrated in the accompanying drawing in which:

Figure I is a sectional elevation through the top of a sleeve valve engine illustrating one embodiment of the invention.

Figure II is an enlarged sectional view through the lower portion of the cylinder head shown in Figure I.

Figure III is a sectional plan taken on the line III—III of Figure II.

Figure IV is an enlarged detailed section of the head showing a modified form of take up device for the junk ring applied thereto, and

Figure V is a detail perspective of the take up device shown in Figure IV.

Referring to the drawing (10) represents a cylinder in which is disposed the inner

and outer sleeve valves (11 and 12) as shown in Figure I. A piston (13) is mounted within the inner sleeve and a cylinder head (14) projects into the upper end of the sleeves and is provided with a central upstanding portion (15) projecting through the cylinder cover (16) and secured thereon by means of a nut (17), all of which construction is that generally employed in what is known as the Knight sleeve valve motor. The cylinder head (14) is provided with an annular recess (18) in the outer wall thereof in which is disposed a packing or junk ring (19) and superimposed upon the upper end of the junk ring is a retaining or tightening ring (20) preferably formed of relatively soft metal. The retaining ring may be made from a metal having a different coefficient of expansion from that of the junk ring, such different coefficient of expansion being chosen for retaining ring and junk ring respectively as will compensate for any change in the longitudinal width of the groove due to the temperature changes. After these rings have been assembled upon the head, tightening of the junk ring is effected by widening the retaining ring, or the forming of enlargements thereon which may be done by driving a punch or other suitable tool into the ring at certain intervals as indicated at (21) to produce a lateral spreading of the particles of metal to take up lost motion between the parts. Thus the junk ring is urged upon the annular rib portion (22) of the head and is prevented from shifting longitudinally of the latter and consequently the objectionable noises usually encountered in engines of this type, due to the striking of the ring against the head, are eliminated. As the rings become worn they may be tightened from time to time by spreading the metal of the retaining ring in the manner described and in this way the junk ring may be kept tight at all times.

In the modification shown in Figures IV and V the construction of the head and junk ring is the same as that shown in Figures I and II, the difference being in the modified form of retaining ring indicated at (23). This member comprises a split ring constructed of spring material and is corrugated as indicated in Figure V or formed with a series of yieldable spring-like portions (24) acting to urge the junk ring upon the head at all times and thereby eliminat-

ing the sudden striking of the ring against the head during the reciprocation of the sleeve valves within the cylinder.

It will be apparent that the invention shown and described herein is susceptible of various modifications, embodiments and arrangements to suit special or varying conditions and I wish it to be understood that the terms which I have used are merely descriptive and not limiting and that it is my intention to include any and all modifications which come within the scope of the invention as defined in the appended claims.

What I claim and desire to secure by Letters Patent is:

1. In a reciprocating engine, a cylinder, a head projecting therein, a sleeve disposed within the cylinder around the head, the head being provided with an annular recess in the outer wall thereof, a packing ring disposed within said recess, and a member mounted within the recess upon one end of the packing ring, said member being forced into engagement with said head and packing ring at certain intervals capable of being forced, by mechanical operation thereon, into contact with both the head and ring.

2. In a reciprocating engine, a cylinder, a head projecting therein, a sleeve disposed within the cylinder around the head, the head being provided with an annular recess in the outer wall thereof, a packing ring disposed within said recess, and a retaining ring of relatively soft metal interposed between the head and one end of the packing ring, said retaining ring being forced into engagement with said head and packing ring to prevent longitudinal displacement of the latter by driving a tool therein to spread the metal at predetermined intervals.

3. In a reciprocating engine, a cylinder head having an annular recess in the outer wall thereof, a packing ring within said recess and a tightening ring disposed within the recess upon one end of the packing ring, said tightening ring being forced into engagement with said head and packing ring to prevent longitudinal displacement of the latter by driving a tool therein to spread the metal at predetermined intervals.

4. The herein described method of constructing cylinder heads comprising the formation of an annular recess in the head, the placing of a packing ring and a tightening ring end to end within the recess and subsequently driving a suitable tool into the

tightening ring at intervals to spread the material thereof so as to urge the packing ring upon the head.

5. In a reciprocating engine, a cylinder head having an annular recess in the outer wall thereof; a packing ring within said recess; and a tightening ring disposed within said recess between the packing ring and adjacent wall of the recess, said tightening ring having rigid lateral off-set portions on either side thereof contacting respectively with the packing ring and said recess wall.

6. In a reciprocating engine, a cylinder head having an annular recess in the outer wall thereof; a packing ring within said recess; and a tightening ring disposed within said recess between the packing ring and adjacent wall of the recess, said tightening ring having rigid lateral projecting portions on either side thereof, said portions being displaced from each other along the circumference of said ring.

7. In a reciprocating engine, a cylinder head having an annular recess in the outer wall thereof; a packing ring within said recess; and a tightening ring disposed within said recess above the packing ring and adjacent wall of the recess, said tightening ring having rigid projecting portions on one side thereof at spaced intervals adapted to contact with the edge of the packing ring to secure the same firmly and non-movably in position on the cylinder.

8. The herein described method of constructing cylinder heads which consists in forming an annular groove in said head, placing a packing ring and a tightening ring in adjacent end to end position with each other in said recess; and subsequently forcing portions of said tightening ring laterally at intervals along said ring into positive engagement with the adjacent end of said packing ring.

9. The herein described method of constructing cylinder heads which consists in forming an annular groove in said head, placing a packing ring and a tightening ring in adjacent end to end position with each other in said recess; and subsequently forcing portions of said tightening ring laterally at intervals along said ring into positive engagement with the adjacent end of said packing ring and the adjacent side of said recess.

In testimony whereof, I affix my signature.

CHARLES Y. KNIGHT.
